FUSE

Filed Dec. 19, 1931

Fig. 2.

Inventor

IRWIN G. RODER.

By *Clarence O'Brien*,
Attorney

UNITED STATES PATENT OFFICE

IRWIN G. BOODER, OF BROOKLYN, NEW YORK

FUSE

Application filed December 19, 1931. Serial No. 582,117.

The present invention relates to a new and useful improvement in fuses, and more particularly it pertains to fuses for cutting out electric circuits when an overload has been imposed thereon.

It is one of the primary objects of the invention to provide an electric fuse which is simple in construction, economical of manufacture, and highly efficient in its operation.

10 It is a further object of the invention to provide a fuse in which none of the parts or elements are consumed during an operation of the fuse to break an electric circuit.

With the above and other objects in view, 15 reference will be had to the accompanying drawing, wherein;

Figure 1, is a longitudinal sectional view of a fuse constructed in accordance with the present invention, and

20 Figure 2, is a top plan view of the fuse. Referring more particularly to the drawing, the fuse comprises a main body portion 5 which is formed of porcelain or other suitable similar non-conducting material.

25 The body portion 5 has a circular flange 6 which extends therefrom to form a cup or the like 7. The cup 7 is provided with a lining 8 of conducting material and said lining preferably has a tight fit within the cup like portion 7. The lining 8 has a flange 9 which overhangs the open end of the flange 6 and extends slightly therebeyond as indicated at 10.

The reference numeral 11 designates a shell 35 which is provided with a screw thread and forms the means for attachment of the parts in a cut-out. This shell has screw threaded engagement with the flange 9 of the lining 8 as indicated at 13 in Figure 1 and this forms

40 the means by which the shell is held in position upon the main body portion 5. Interposed between the shell and the flange 9, there is a flat disk like member 15 of non-conducting material and this member is held in position by means of an inwardly projecting flange 16 on the shell 11.

The member 15 carries a central electrode 20. This central electrode 20 is in the form of a conducting bar or pin having a head 21 and 45 it is passed through an opening 22 in the

member 15. This electrode 20 projects to a point near the bottom of the cup like portion of the main body portion 5, its lower end being spaced from the bottom of said cup like portion and from the side walls of the lining 8.

In the bottom of the cup like member, there is a conducting medium 18 which in the present instance is mercury.

Thus it will be apparent that the fuse has 60 two contacts, one of which is provided by means of the shell 11, and the other being provided by means of the head 21 of the electrode 20. Electric current passing through either of these contacts will pass through the 65 mercury 18 and the circuit will be thereby completed between these two contacts.

Immediately the circuit is subjected to a heavy load, the mercury is dispersed and the circuit is broken thus preventing damage to 70 the circuit or any devices which may be included therein.

After the fuse has operated in the manner heretofore described to break the circuit, it is only necessary to remove the fuse invert 75 the same when the mercury will be collected and the fuse is again ready for use.

Thus it will be apparent that the present invention provides a fuse in which the aforementioned operations are efficiently carried 80 out.

While the invention has been herein illustrated in what may be termed a preferred form, it is to be understood that the invention is not to be limited to the specific construction herein shown, but that it may be carried out in other forms without departing from the spirit thereof.

Having thus described the invention, what is claimed as new and what it is desired to secure by Letters-Patent of the United States, is:

1. A fuse comprising a cup shaped member of non-conducting material, a tubular member of conducting material forming a lining for the cup-shaped member, a shell of conducting material embracing said cup-shaped member, and having electrical connection with the lining member, a non-conducting member carried by said conducting lining, 95 100

and held thereon by said shell, a conducting member carried by said last mentioned non-conducting member, and extending into the cup-shaped member, and a fluid conducting medium carried by said cup shaped member and forming an electrical connection between the lining of the cup-shaped member and said electrode.

2. A fuse comprising a cup-shaped member of non-conducting material, a tubular member of conducting material forming a lining for the cup-shaped member, a shell of conducting material embracing said cup-shaped member, and having electrical connection with the lining member, a non-conducting lining held in position in the cup like member by the shell, a conducting member carried by said last mentioned non-conducting member and extending into the cup-shaped member, and a fluid conducted medium carried by said cup-shaped member and forming an electrical connection between the lining of the cup shaped member and said electrode.

3. A fuse comprising a cup-shaped member of non-conducting material, a lining for said cup-shaped member, a shell, said shell adapted to engage said lining to retain the shell in position on the cup-shaped member, an insulating member carried by said lining, and an electrode carried by said insulating member and projecting into the cup-shaped member in spaced relation with the lining thereof.

4. A fuse comprising a cup-shaped member, a lining therefor, a flange projecting from said lining and extending beyond the outer face of the cup-shaped member, a shell, said shell having screw threaded engagement with the flange of the lining, an insulating member carried by the lining and held thereon by said shell, an electrode carried by said insulating member and projecting into the cup like member in spaced relation with the lining thereof, and mercury carried in the cup-shaped member and adapted to establish an electrical connection between the lining and the electrode.

5. A fuse comprising a cup-shaped member of non-conducting material, a conducting lining for said cup-shaped member, a flange projecting from said lining, and extending to a point beyond the outer face of the cup-shaped member, said flange having a screw thread upon its peripheral edge, a threaded shell member, said shell member adapted to receive the cup-shaped member and have threaded engagement with the flange of the lining therefor to retain the shell in position upon the cup-shaped member, a non-conducting member carried by said lining, and secured in position thereon by said shell, an electrode carried by said non-conducting material and projecting into the cup-shaped member in spaced relation with the lining

thereof, and a volume of mercury carried by the cup-shaped member and adapted to complete an electrical circuit between the lining of the cup-shaped member and said electrode.

In testimony whereof I affix my signature. 70
IRWIN G. ROODER.
